2,473,398

DEVICE ON WHICH TO FORM MINIATURE
LADDERS, ETC.

Frank Spano, Union City, N. J.

Application March 28, 1946, Serial No. 657,776

9 Claims. (Cl. 28—15)

1

Model ships or sailing vessels require miniature or imitation ladders of various shapes and sizes. It is an object of my invention to provide a jig or form on which or by means of which any one can easily construct the ladders required in order to simulate on a small scale the actual ladders on full sized ships.

For this purpose, I provide a supporting base with bridges and abutments over which the threads for the vertical shrouds and horizontal rungs may be stretched and secured while glue or lacquer is applied to unite the threads at the points of crossing.

Fig. 1 is a front view of the lower end of a device embodying one form of my invention showing the threads in place to form three ladders.

Fig. 2 is a front view of the upper end of the device (not in use).

Figs. 3 and 4 are side views of the parts shown in Figs. 1 and 2, respectively, parts being broken away.

Fig. 5 is an end view of the lower right hand part of Fig. 1, parts being broken away.

Fig. 6 is a fragmentary end view of a modification, parts being broken away.

The foundation or base 10 and the bridges 11 and 12 may be formed of wood or any other suitable material. The bridge 12 is mounted near one end of the base and for convenience may have pins 14, 14 detachably inserted in holes in the base. This bridge has notches 15 in its upper edge arranged at suitable intervals for instance, one-eighth of an inch, representing the spacing for the threads corresponding to the shrouds at their lower ends.

The bridge 11 is preferably detachably mounted on the base by pins such as 16, 17 and 18 inserted in holes such as holes in the rows of 19, 20, 21 etc., at a distance above bridge 12 corresponding with the height of the ladder to be formed which may be from one-half inch to twelve inches depending upon the size of the ship model. This bridge has pins projecting outwardly around which the vertical threads may be caught.

The ends and sides of the base are provided with slits 22, 23, respectively, arranged at suitable intervals such as one-eighth of an inch more or less corresponding to the spacing of the notches in bridge 12 or somewhat further apart as in Fig. 2. In fact the same base can have the spacing different at one end than at the other end.

Two notched bridges may be provided for use

2

with the same support, the notches in each bridge corresponding with the slits at the end of the support with which it is to be used. As the walls of these slits are intended to act as resilient friction jaws for holding the ends of the threads, I preferably provide resilient rubber or similar strips 24 and 25 in which these slits are formed. These strips may be secured to the base in any suitable manner and in fact may be detachable so that they may be removed and replaced or strips of different slit-spacings may be substituted.

These abutment strips may be inserted in the edges of the base as shown in Figs. 4 and 5 or may be mounted on the base as at 26 so as to have slits 27 substantially in the plane of the tops or outer edges of the bridges (Fig. 6).

In order to form a tapered ladder as shown in Fig. 1, the substantially longitudinal threads 30 are passed around a pin such as 17 on bridge 11 guided in the notches in bridge 12 and the ends pulled tightly into the slits 22 in the bottom strip 24. The cross threads 31 are then applied over the substantially longitudinal threads, their ends being secured in the slits 23 in the side strips 25. A quick drying glue, cement or lacquer is then applied to the points of crossing of the threads and allowed to set. The cross threads are then cut off adjacent the sides of the ladder and the lower ends of the substantially longitudinal threads below the bottom cross thread are cut off to the length required for the installation.

By providing pins 35, one-eighth of an inch in diameter spaced apart one-eighth of an inch 35 in the upper bridge 11, it is possible to loop threads around these pins and then stretch the threads over bridge 12 and into the properly spaced slits in the lower strip 24 and then apply transverse or cross threads as above so as to 40 form a ladder or other network of uniform width, as shown to the right of Fig. 1.

In each case, it is thus possible to form uniform and neat ladders according to the more or less conventional patterns and size of ships models.

45 By reversing the base, after a number of ladders such as shown in Fig. 1 have been completed, and mounting another bridge 11 on the base and another bridge 12 adjacent the inverted bottom end, the remaining surface of the base may be 50 utilized for making other networks.

I claim:

1. A form for the construction of miniature ladders consisting of a base having raised bridges for supporting substantially longitudinal threads, a slotted resilient abutment for fric-

tionally anchoring the ends of threads supported on said bridges and fixed slotted resilient side strips for anchoring the ends of cross threads supported on the substantially longitudinal threads.

2. A form for the construction of miniature ladders consisting of a base, a raised bridge supported thereon having spaced notches for supporting threads, a second raised bridge having pins around which threads may be looped, a resilient anchorage strip having spaced slits corresponding in spacing with the spacing of the notches whereby threads may be looped around said pins supported in said notches and anchored in said strip and fixed resilient side strips having slits in the approximate plane of the supporting edges of the bridges.

3. A form for the construction of a net work of threads consisting of a base, a bridge supported thereon above the surface thereof and having notches for supporting substantially longitudinal threads, a second raised bridge spaced apart therefrom and in the plane with the first bridge having pins around which substantially longitudinal threads may be looped, an anchorage strip having spaced slits for receiving the free ends of threads supported in said notches and resilient side anchorage strips extending substantially at right angles to said bridges and having spaced slits for receiving cross threads and holding them in a stretched condition.

4. A form for the construction of a net work of threads comprising a rectangular base having end members and side members, resilient strips at the outer edges of said end and side members, the strip along at least one of the end members having spaced slits, a bridge member mounted on the top surface of the base and disposed transversely thereof, said bridge member having spaced notches on its upper surface adapted to cooperate with the slits in the strip along said end member for receiving and holding threads in spaced relation and another bridge member adjustably mounted on the top surface of the base and disposed remote from and parallel to said first-named bridge member and having means for receiving and holding said threads in converging relation, the strips along the side members having spaced slits for receiving and holding the ends of threads crossing said first-named threads in a stretched condition.

5. A device for forming a net work of intersecting threads comprising a base, a raised bridge near one end having spaced notches for supporting substantially longitudinal threads, a second raised bridge spaced apart from the first bridge and having means for supporting said threads, means at the end of the base having spaced slits with resilient jaws into which said threads can be drawn and held and means at the sides of the base having spaced slits with fixed resilient jaws for holding transverse threads stretched across the substantially longitudinal threads.

6. A device for forming a net work of intersecting threads comprising a base, a raised bridge carried by the base and having means for supporting threads thereon, a second bridge parallel to the first bridge having spaced notches for supporting threads from the first-mentioned bridge, a resilient strip carried by said base parallel to said bridges and having spaced slits for receiving and holding threads stretched from the first bridge over the second bridge and fixed resilient strips at the sides of the base having spaced slits for receiving and holding threads stretched

across the threads which are supported on said bridges.

5 7. Apparatus for forming miniature ladders comprising a base having fixed slotted resilient strips along its side edges and a slotted resilient strip across one end and having rows of holes and a removable bridge having pins for inserting into said holes in the base, said bridge also having projecting pins around which substantially longitudinal threads may be held while their ends are secured in slits in the strip at the end of the base, the strips along the side edges of the base being adapted to hold transverse threads stretched across the substantially longitudinal threads.

15 8. A device on which to form a miniature ladder comprising a base having fixed resilient strips at the opposite side edges and one extending transversely of the base, said strips having spaced slits for resiliently holding threads, a bridge extending transversely of the base and having projections above the level of the base around which substantially longitudinal threads may be held at one end of a ladder to be formed while the opposite ends of the threads are held stretched in the slits of the transverse strip, said side strips having their spaced slits at the approximate level of the bridge for holding transverse stretched threads supported by the substantially longitudinal threads, said base being provided with means for permitting a change in the distance between the transverse bridge and the transverse strip so as to change the length of the ladder to be formed.

35 9. A device on which to form a miniature ladder comprising a base having fixed resilient strips at the opposite side edges and at least one end, said strips having spaced slits for resiliently holding stretched threads, a bridge extending transversely of the base and having spaced projections around which substantially longitudinal threads may be held at one end of a ladder to be formed while the opposite ends of the threads are held stretched in the slits of the strip at the end of the base and a notched bridge supported by the base between the first-mentioned bridge and the strip at the end of the base for positioning the threads at the other end of the ladder, said side strips having their spaced slits at the approximate level of the bridges for holding transverse threads stretched across the substantially longitudinal threads.
